ADJUSTABLE COVER FOR FLUSH TANKS

Jacob Levine, Brooklyn, N. Y., assignor of one-half to Harold Terr, Brooklyn, N. Y.

Application May 18, 1940, Serial No. 335,883

4 Claims. (Cl. 4—68)

This invention relates to new and useful improvements in an adjustable cover for flush tanks.

The invention contemplates the construction of a cover for flush tanks which is characterized by abutment members adjustably mounted on the bottom thereof and adapted to extend into the top of a tank and engage the side walls thereof so that the cover is firmly held upon the tank irrespective of the fact that it is larger than the top dimensions of the tank.

More specifically, the invention proposes to provide the cover with lugs at its bottom side, and to adjustably mount the abutment members on these lugs in a manner so that they may be adjusted to various positions according to the size of the tank for which the cover is intended.

Still further the invention proposes to characterize the abutment members by headed bolts slidably mounted on the lugs previously mentioned, and tubular bushings of resilient material mounted on the bolts and adapted to contact the walls of the tank.

Still further the invention proposes a simple arrangement by which the abutment members may be properly positioned on the cover to fit any particular tank.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a flush tank with a cover mounted thereon constructed in accordance with this invention.

Fig. 2 is a bottom perspective view of the cover, per se.

Fig. 3 is a fragmentary enlarged vertical sectional view taken on the line 3—3 of Fig. 4.

Fig. 4 is a fragmentary vertical sectional view taken on the line 4—4 of Fig. 3.

Fig. 5 is a horizontal sectional view taken on the line 5—5 of Fig. 4.

Fig. 6 is a fragmentary vertical sectional view taken on the line 6—6 of Fig. 1.

Fig. 7 is a sectional view similar to Fig. 6 but illustrating a modified construction.

Fig. 8 is a horizontal sectional view taken on the line 8—8 of Fig. 7.

The adjustable cover for flush tanks, in accordance with this invention, comprises a rectangular cover 10 of the usual porcelain material and hav-

ing a top wall portion 10^a and edge flange portions 10^b on three sides thereof. This is the usual form of the cover of a flush tank, such as for the tank 11 illustrated in Fig. 1. A plurality of abutment members 12 are adjustably mounted on the bottom of the cover 10 and are adapted to extend into the top of the tank 11 and engage the side walls thereof to securely hold the cover in position irrespective of the fact that the cover may be slightly too large for the tank.

Each abutment member 12 includes a tubular bushing 12^a of resilient material, such as rubber, supported by a bolt 14. The bolts 14 have heads 14^a which are slidably mounted in slots 15 having overhanging edges 15^a. These slots 15 are formed in lugs 16 on the sides of the cover 10. These lugs 16 project from thickened portions 10^c extended around the three sides of the top wall 10^a of the cover 10. These thickened portions 10^c are immediately adjacent the edge flanges 10^b. A nut 17 threadedly engages on the outer end of each bolt 14, and abuts the ends of the tubular bushings 12^a. The slots 15^a are arranged at right angles to the sides of the cover 10.

The cover, in accordance with this invention, is used as follows:

The nuts 17 are loosened and the abutment members 12 are shifted in the slots 15 until the sides of the abutment members strike the inner faces of the side walls of the tank 11, as illustrated in Fig. 6. The abutment members 12 may be properly positioned by trial, that is, it is necessary to lift the cover 10 off the tank several times and shift the abutment members 12 to new positions until they reach the correct positions. Then the nuts 17 are turned tight to lock the bolts 14 in stationary positions. Once the correct adjustment of the abutment members 12 has been attained it is not necessary to change it any more, except in the event that the tubular bushings 12^a shrink or deteriorate.

In Figs. 7 and 8 a modified form of the invention has been disclosed which distinguishes from the prior form in the fact that means has been provided for assisting in properly locating the abutment members 12 in positions to abut the inner faces of the side walls of the tank 11. In accordance with this form of the invention the head 14^a of each bolt is provided with roughened or serrated faces 14^{aa} engaging serrations 15^{aa} extended along the overhanging portions 15^a of the slots 15. A leaf spring 19 is mounted on each bolt head 14^a, and acts against the bases of the slots 15 and serves to urge the serrations 14^{aa} and 15^{aa} into contact with each other. A passage 20

is formed through the flanges 10^b of the cover adjacent each slot 15. These passages terminate in the edges 10^{bb} of the flanges 10^b. A cord or wire 21 is threaded through each passage 20, and through apertures 14' formed in the bolt heads 14^a. The ends 21^a of the cords or wires 21 are knotted.

In other respects this form of the invention is similar to the prior form and like parts are indicated by like reference numerals.

The adjustable cover, in accordance with this form of the invention, is used as follows:

The nuts 17 are loosened and the abutment members 12 are shifted to the free ends of the slots 15. The cover 10 is then placed on the tank 11. The strings or wires 21 are pulled so as to move the abutment members 12 firmly against the inner faces of the side walls of the tank 11. The cover 10 is then removed and the nuts 17 are tightly screwed down to hold the members 12 in their new positions. The strings or wires 21 are then removed. The cover is now used in the conventional manner.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An adjustable cover for flush tanks, comprising a cover for flush tanks, and abutment members adjustably mounted on the bottom of said cover and adapted to extend into the top of a tank and engage the side walls thereof, and comprising bolts slidably mounted on said cover, resilient tubular bushings on said bolts, and means for locking said bolts in fixed positions.

2. An adjustable cover for flush tanks, comprising a cover for flush tanks, and abutment members adjustably mounted on the bottom of said cover and adapted to extend into the top of

5 a tank and engage the side walls thereof, said abutment members comprising bolts having their heads slidably engaged in slots provided with overhanging edges, tubular bushings mounted on said bolts, and nuts threadedly engaged on the bolts and abutting the tubular bushings, and when turned tight adapted to force the heads of the bolts against the edges of the overhanging portions of said slots.

10 3. An adjustable cover for flush tanks, comprising a cover for flush tanks, and abutment members adjustably mounted on the bottom of said cover and adapted to extend into the top of a tank and engage the side walls thereof, said 15 abutment members comprising bolts having their heads slidably engaged in slots provided with overhanging edges, tubular bushings mounted on said bolts, and nuts threadedly engaged on the bolts and abutting the tubular bushings, and when 20 turned tight adapted to force the heads of the bolts against the edges of the overhanging portions of said slots, said slots being formed in lugs arranged on the portions extended along the sides of said cover.

25 4. An adjustable cover for flush tanks, comprising a cover for flush tanks, and abutment members adjustably mounted on the bottom of said cover and adapted to extend into the top of a tank and engage the side walls thereof, said 30 abutment members comprising bolts having their heads slidably engaged in slots provided with overhanging edges, tubular bushings mounted on said bolts, and nuts threadedly engaged on the bolts and abutting the tubular bushings, and when 35 turned tight adapted to force the heads of the bolts against the edges of the overhanging portions of said slots, the contacting faces of said 40 bolts and overhanging portions of the slots being provided with inter-engaging serrated portions, resilient means urging said serrations into engagement with each other, and flange elements connected with said bolts and extending through passages into said cover to points where they may be pulled to move the bolts along said slots.

JACOB LEVINE.
